UNITED STATES PATENT OFFICE.

ANDREW BARNA, JR., OF CHICAGO, ILLINOIS.

CIGAR OR CIGARETTE LIGHTER.

Application filed April 14, 1922. Serial No. 552,466.

To all whom it may concern:

Be it known that I, ANDREW BARNA, Jr., a citizen of Hungary, residing at Chicago, in the county of Cook and State of Illinois, have invented certain new and useful Improvements in Cigar or Cigarette Lighters, of which the following is a specification.

This invention relates to certain new and useful improvements in cigar or cigarette lighters, particularly adapted for use upon motor vehicles whereby the occupant of the motor vehicle may readily light a cigar or cigarette without the employment of matches.

An object of the invention is to provide a cigar or cigarette lighter capable of general use and employing electric current for heating a suitable resistance from which the cigarette or cigar may be lighted, the construction being of such nature as to generally simplify an improved device of this character.

Another object of the invention is to so construct a cigar or cigarette lighter of the above kind as to enable the same to be made cheaply and easily by the provision of a plurality of simple parts which may be assembled for producing a device of light weight and of such a construction as to not readily get out of order from continued use.

With the above general objects in view the invention consists in the novel combination and arrangement of parts hereinafter more fully described in connection with accompanying drawings, and in which like reference characters designate corresponding parts throughout the several views.

In the drawings:

Figure 1 is an elevational view of the cigar or cigarette lighter constructed in accordance with the present invention.

Figure 2 is a vertical and central or longitudinal sectional view taken on line II-II of Figure 1.

Figure 3 is a transverse sectional view on line III-III of Figure 2.

Figure 4 is a view similar to Figure 3 taken on line IV-IV of Figure 2.

Figure 5 is an elevational view of one of the conductor block sections.

Figure 6 is a top plan view of the device as shown in Figure 5.

Figure 7 is a view similar to Figure 5 on another of the conductor blocks and

Figure 8 is a view similar to Figure 6 of the device shown in Figure 7.

Referring more in detail to the several views, the invention embodies an elongated cylindrical casing 5 having end caps 6 and 7, the latter cap being readily openable and detachably fastened in place by means of a hook shaped keeper 8 preferably of resilient sheet metal and fastened interiorly of the casing 5 by means of a rivet 9 or the like so that its hooked end will be disposed to engage in an elongated slot 10 provided in the rim of the cap 7, the said hooked shape end of the keeper being slidable through a slot in the wall of the casing 5 as clearly shown in Figure 2. The casing 5 is provided with an insulating lining throughout as at 11, which lining may be of mica and which extends between the casing 5 and the keeper 8 so as to insulate the latter from said casing.

The casing 5 is divided into two equal longitudinal compartments from the cap 6 to a point inwardly of the cap 7 by means of a strip 12 of insulating material, which strip is relatively thick and rigid. At the inner end of the casing are provided a pair of similar insulator block sections 13 which are substantially semi-cylindrical in form and disposed at opposite sides of the partition strip 12 with the flat face 14 of each section 13 flatly engaging the adjacent base of the partition 12 and with the arcuate face 15 of said section snugly engaging the interior or inner face of another layer 16 of mica which lines the casing 5 and which contacts with the lining layer 11. The blocks 13 together with the partition 12 thus provide a solid cylindrical plug at this end of the casing 5 and as the blocks 13 are made of conducting material they may be readily attached to feed and return wires 17 and 18 which may lead to any source of electrical supply.

The block sections 13 are preferably held against movement when properly positioned, by means of dowel pins 19 which enter suitable sockets 20 provided in the blocks 13 and openings 21 provided in the casing 5. As is shown, the wires 17 and 18 are attached to the inner ends of the

blocks 13 by means of stud screws 22 which are threaded into suitable threaded sockets 23 provided in the inner ends of said block sections 13, and the wires 17 and 18 also 5 pass outwardly through openings 24 provided in the cap 6.

At the outer end of the casing 5 and spaced considerably from the blocks 13 are further somewhat similar block sections 25, 10 said block sections 25 being of substantially semi-cylindrical form and having flat faces 26 flatly engaging the faces of the partition 12 and curved faces 27 snugly fitting the inner face of the lining 16. The block sections 25 are fastened by means of dowel pins 28 against movement in the casing, said dowel pins entering apertures in the casing 5 and sockets 29 in the block sections 25. In this way material economy is had 20 and at the same time rigidity and strength is provided for.

The block 13 at one side of the partition 12 is connected with the block 25 at the same side by means of a conductor wire 36 25 which is attached to the blocks at opposite ends by means of stud screws 37 entering suitable internally threaded sockets in the adjacent ends of said blocks. The other block 13 has one end of a sheet metal strip 38 fastened thereto by means of a stud screw 39, and this strip extends upwardly normally in contact with the inner surface of the lining 16 and has a push button fastened to the upper or outer free end 35 thereof as at 40, said push button slidably extending outwardly through aligned openings in the linings 11 and 16 and the casing 5 at the lower end of the adjacent block section 25. The last mentioned block section 40 is provided with a longitudinal groove 41 in which the outer end of the resilient strip 38 is freely movable and said strip is of such width as to be out of contact with the side walls of the groove 41.

45 A resistance 42 of suitable material and preferably of substantially C shape in plan has its terminals extended at right angles thereto to provide supporting legs 43 whose free ends are attached to the blocks 25 by means of stud screws 44 entering sockets in the adjacent ends of the block sections 25. In this manner the resistance 42 is effectively rigidly supported at the open end of the casing, and by pressing 50 upon the push button 40, the free end of contact strip 38 may be brought into contact with the bottom or inner wall of the groove 41 to thereby establish an electric circuit from the wire 17 to block 13, wire 36 to block 25, one of the legs 43 and resistance 42, and then to the other leg 43 and the other block 25 to the strip 38 to the other block 13 and to wire 18. In use the resistance 42 will become incandescent and extremely hot so that a cigar or cigarette may

be readily lighted thereon upon removal of the cap 7.

The cap 7 is preferably hinged to the casing 5 as at 45 opposite the opening 10 provided therein, and in order that the cap 7 may be automatically opened when the keeper 8 is released, a spring strip bears against the same under tension above the pivot point 45. This strip is denoted by the numeral 46 and preferably embodies a longitudinal portion riveted as at 47 to the casing 5 and disposed between the linings 11 and 16 as well as projecting slightly into the longitudinal slot 48 in the adjacent block section 25. A mica disk 49 is preferably provided to cover the outer end of the partition 12 and block sections 25.

In operation the wires 17 and 18 may be associated with a suitable source of electricity such as the storage battery of a motor vehicle and the said wires may also be of such length as to be readily wound upon a spring drum or reel so that when the casing is grasped the wires may be extended to within convenient reach of the operator for lighting a cigar or cigarette, which action may be readily accomplished by pressing the push button 50 of the keeper 8 and then pressing inwardly on the push button 40 of the resilient switch contact strip 38. When the lighter is no longer desired to be used the cover 7 may be swung to closed position and then retained by the keeper 8 and the flow of electric current will be cut off by release of the push button 40.

From the foregoing description, it is believed that the construction and operation as well as the advantages of the construction will be readily understood and appreciated by those skilled in the art.

What I claim is—

1. A cigar or cigarette lighter comprising a cylindrical casing, a longitudinal central partition strip of insulating material extending substantially from end to end of said casing, a pair of substantially semi-cylindrical blocks disposed at opposite sides of the partition at the inner end of the casing and formed of conducting material for electricity, means to attach conductor wires to the outer ends of said block sections, a further pair of block sections within the casing at opposite sides of the partition strip and spaced from the first named block sections, a resistance adapted to be rendered incandescent by an electric circuit having terminals fixed to the last named block sections outwardly of the latter, means electrically connecting one of the first named block sections with one of the last named block sections at the same side of the partition, and a resilient switch member attached to the other of the first named block sections and manually movable to electrically con-

nect the latter block section with the other of the second named block sections whereby a circuit is established through the resistance.

5. 2. A cigar or cigarette lighter comprising a cylindrical casing, a longitudinal central partition strip of insulating material, a pair of substantially semi-cylindrical blocks disposed at opposite sides of the partition at 10 the inner ends of the casing and formed of conducting material for electricity, means to attach conductor wires to the outer ends of said block sections, a further pair of block sections within the casing at opposite 15 sides of the partition strip and spaced from the first named block sections, a resistance adapted to be rendered incandescent by an electric circuit having terminals fixed to the last named block sections outwardly of the 20 latter, means electrically connecting one of the first named block sections with one of the last named block sections at the same side of the partition, and a resilient switch member attached to the other of the first 25 named block sections and manually movable to electrically connect the latter block section with the other of the second named block sections whereby a circuit is established through the resistance, and dowel 30 pins retaining the block sections against moving in the casing.
3. A cigar or cigarette lighter comprising a cylindrical casing, a longitudinal central partition strip of insulating material extending substantially from end to end of 35 said casing, a pair of substantially semi-cylindrical blocks disposed at opposite sides of the partition at the inner end of the casing and formed of conducting material for 40 electricity, means to attach conductor wires to the outer ends of said block sections, a further pair of block sections within the casing at opposite sides of the partition strip and spaced from the first named block 45 sections, a resistance adapted to be rendered incandescent by an electric circuit having terminals fixed to the last named block sections, outwardly of the latter, means electrically connecting one of the first named 50 block sections with one of the last named

block sections at the same side of the partition, a resilient switch member attached to the other of the first named block sections and manually movable to electrically connect the latter block section with the other of the second named block sections whereby a circuit is established through the resistance, dowel pins retaining the block sections against movement in the casing, insulating linings for the interior of the casing between the latter and the block sections, and said second named block sections having longitudinal grooves and the contact member being in the groove of one of the second named block sections.

4. A cigar or cigarette lighter comprising a cylindrical casing, a longitudinal central partition strip of insulating material extending substantially from end to end of said casing, a pair of substantially semi-cylindrical blocks disposed at opposite sides of the partition at the inner end of the casing and formed of conducting material for electricity, means to attach conductor wires to the outer ends of said block sections, a further pair of block sections within the casing at opposite sides of the partition strip and spaced from the first named block sections, a resistance adapted to be rendered incandescent by an electric circuit having terminals fixed to the last named block sections outwardly of the latter, means electrically connecting one of the first named block sections with one of the last named block sections at the same side of the partition, a resilient switch member attached to the other of the first named block sections and manually movable to electrically connect the latter block section with the other of the second named block sections whereby a circuit is established through the resistance, said block sections having threaded sockets in the opposite ends thereof, and the electrical connections between the pairs of blocks and between the blocks and the wires and between the blocks and the resistance including stud screws engaging said sockets.

In testimony whereof I affix my signature.

ANDREW BARNA, JR.
